UNITED STATES PATENT OFFICE.

HARRY ELSWORTH DE VAUGHN, OF MORGANTOWN, WEST VIRGINIA, ASSIGNOR TO
WALTER A. JONES, OF MORGANTOWN, WEST VIRGINIA.

DEVICE FOR SUPPORTING GLASS CYLINDERS.

1,187,276.

Specification of Letters Patent. Patented June 13, 1916.

Application filed November 9, 1914. Serial No. 871,076.

To all whom it may concern:

Be it known that I, HARRY ELSWORTH DE VAUGHN, a citizen of the United States, residing at Morgantown, in the county of 5 Monongalia and State of West Virginia, have invented new and useful Improvements in Devices for Supporting Glass Cylinders, of which the following is a specification.

10 This invention relates to that class of device known as a "horse" utilized for supporting long glass cylinders while the latter are being cut into lengths.

One of the objects of the invention is to 15 provide means for so mounting the cylinder-supporting arms that the latter will automatically adjust themselves to inequalities in the cylinder, and will all bear upon the glass with substantially the same pressure, whereby a uniform support for the 20 cylinder, throughout its length, is provided.

A further object is to so mount the cylinder-supporting arms that the severed lengths 25 of the cylinder after cutting, will be uniformly supported, and relative movement of the severed lengths, whether longitudinally or transversely, is avoided.

A further object is to provide a support 30 of the character referred to with cylinder-supporting arms which may be readily placed into or removed from their operative position, to facilitate assembling, and also to permit ready substitution for repairs, and the like.

35 The invention will be hereinafter fully set forth and particularly pointed out in the claim.

In the accompanying drawing:—Figure 1 is a plan view illustrating my improved 40 horse. Fig. 2 is a side elevation. Fig. 3 is an end view.

Referring to the drawing, the supporting frame comprises a series of standards 10 connected at their tops by a longitudinal 45 member or backbone 11, formed of two angle irons united to form a longitudinal rib 12 and horizontal flanges 13. The standards 10 are also connected by a tubular bar 14 extending parallel with the backbone 11 and below the latter. Pivots mounted upon 50 the bar 14 are a plurality of sleeves 15 which are provided with telescoping arms 16, the outer end of each arm 16 being provided with an eye or opening 17. The cylinder-supporting arms 18 are provided with

shanks 19 which extend through the eyes or openings of the respective arms 16, the shank of each of said arms 18 terminating in a hook 20 constructed to engage any one of a series of openings 22, in the flanges 13. 60 Coil springs 23 are interposed between the upper ends of the respective sleeves 15 and the undersides of the cylinder-supporting arms 18, said springs serving to yieldingly sustain said arms. The pivot ends of the sleeves 15 are provided with collars surrounding the bar 14, and said collars are definitely spaced from each other predetermined distances by spacing collars 25.

In the use of my improved horse, the 70 sleeves 15 are properly spaced by the spacing sleeves or collars 25, and the device is placed upon the floor adjacent the usual glass furnaces. After a cylinder has been drawn in the usual way it is removed from 75 the drawing apparatus by a suitable take-down device, and placed upon the arms 18. When the cylinder is laid upon the said arms, the various springs 23 are compressed, 80 the arms 16 sliding downwardly into the sleeves 15. Inasmuch as each arm is free to yield independently of the others, the cylinder will be uniformly and evenly supported throughout its length. The glass 85 may then be severed into suitable lengths in any preferred manner, and after severing the sections will be held without substantial relative movement because of the spacing sleeves 25. Should it become necessary to replace one of the arms 18, the 90 said arm may be readily removed by first withdrawing the arm 16 and then unhooking the arm 18 from the flange 13. The new arm may be readily placed in position 95 by reversing this operation.

Having thus explained the nature of my invention and described an operative manner of constructing and using the same, although without attempting to set forth all of the forms in which it may be made, or all of the forms of its use, what I claim 100 is:—

A device for supporting glass cylinders comprising a frame formed of a series of standards connected at their top by a longitudinal bar having lateral flanges, a second longitudinal bar below the first bar, sleeves each having one end pivotally connected to the lower bar, arms telescoping with said sleeves, supporting arms detachably con- 105 110

needed with the free ends of the respective telescoping arms, said supporting arms having hooks on their inner ends to detachably engage said sleeves, and springs interposed between said sleeves and said supporting arms.

In testimony whereof I have hereunto set

my hand in presence of two subscribing witnesses.

HARRY BISWORTH DE VAUGUE.
